JOHN H. DOMKEE, OF WEST HAVEN, CONNECTICUT, ASSIGNOR TO THE WIRE NOVELTY MANUFACTURING CO., OF WEST HAVEN, CONNECTICUT, A CORPORATION OF CONNECTICUT

BUTTON LOOP

Application filed February 15, 1929. Serial No. 340,245.

The invention relates to improvements in button loops particularly adapted for use on garment straps, the loop being specially adapted to be suspended at the end of a strap 5 in readiness to be clipped over a button the shank of which may be urged therefrom into a smaller retaining loop from which it cannot be unintentionally withdrawn, and the objects of the invention are to provide a two- 10 piece button loop with a button retaining loop member so connected with the suspension member that the lines of the combined loop members present a substantially unbroken interior of compound curves; and to 15 provide a retaining loop member adapted for a pivotal mounting upon the suspension member for movement in opposite directions; and to provide a retaining loop member for a pivotal mounting upon a suspen- 20 sion member portions of which co-operate with the retaining loop member in providing a substantially circular retainer for the shank of a button. With these and other objects in view as may become apparent 25 from the within disclosures the invention consists not only of the particular form herein pointed out and illustrated in the drawing but readily admits of certain modifications within the scope of what herein- 30 after may be claimed.

The following is the description of an embodiment of the invention reference being had to the accompanying drawing in which the Figure 1 is a face view of the device; the 35 Figure 2 is a bottom view; and the Figure 3 is a side elevation.

Referring more particularly to the drawing in which similar numbers refer to similar parts, the device comprises a metal sus- 40 pension member 1 adapted to be suspended from a strap (not illustrated) and providing the button receiving loop 2 having the contracted throat 3 from which the structure diverges to assume the form of a pair of 45 arcs 4-4, the metal being outwardly turned back upon each arc 4 and then bent outwardly to provide the terminals 5-5 in alignment one with the other, and thus extending from their respective sides of the 50 suspension member above the arcs 4-4,

which arcs 4-4 are the lowermost parts of that member, the extremities 6-6 of the terminals 5-5 being upset as illustrated by the Figures 1 and 2. The button retaining member 7 is pivotally mounted upon the terminals 5-5 by means of the eye terminals 8-8 normally engaging the terminals 5-5 in close proximity to the upset extremities 6-6, each of the arms 9-9 from the terminals 8-8 extending downwardly and then 55 bent inwardly toward one another to engage directly under the lowermost parts of the suspension member to there integrally combine to provide the button retaining portion with which the arcs 4-4 co-operate to provide a 60 substantially circular button retainer 10 capable of swinging upon its mounting in both directions out of the general plane of the button loop as illustrated in dotted lines by the Figure 3.

What I claim is:—

1. A two-piece button loop comprising a suspension member provided with a button receiving loop having a contracted throat through which the shank of a button may be urged; a second member partially circular and providing a portion of a button retaining loop; arc portions provided by the lowermost extremities of the first member and co-operating with the second member to provide a 75 circular button retaining member; aligned terminals provided by the first member above its lowermost extremities; and means provided by the aligned terminals and the second member for pivotally assembling the mem- 80 bers.

2. A two-piece button loop comprising a suspension member provided with a button receiving loop having a contracted throat through which the shank of a button may be urged; a second member partially circular and providing a portion of a button retaining loop; arc portions provided by the lowermost parts of the first member and co-operating 85 with the second member to provide a circular button retaining member; aligned terminals provided by the first member above its lowermost parts, each terminal having an upset extremity, and eye terminals provided by the 90 95 100

second member for pivotal engagement upon the aligned terminals.

3. A two-piece button loop comprising a button receiving member having a contracted throat to which the shank of a button may be urged by expanding the loop; a second member providing the lower portion of a button retaining loop; portions provided by the lowermost parts of the button receiving member and cooperating with the lower portion of the second member to provide a button retaining member; aligned terminals provided by the first member above its lowermost parts; and means provided by the aligned terminals and the second member for pivotally assembling the members.
